DESIGN FOR A LAWN SWING OR SIMILAR ARTICLE

Albert H. Adcox, East St. Louis, Ill.

Application August 6, 1937, Serial No. 70,899

Term of patent 14 years

To all whom it may concern:

Be it known that I, Albert H. Adcox, a citizen of the United States, residing in the city of East St. Louis, in the county of St. Clair and State of Illinois, have invented a new, original, and ornamental Design for a Lawn Swing or Similar Article, of which the following is a specification, reference being had to the accompanying drawing, forming part thereof.

In the drawing:

The figure is a perspective view of the lawn swing or similar article showing my new design. The rear and opposite side of the lawn swing are substantially identical, respectively, with the front and the side shown by the drawing.

I claim:

The ornamental design for a lawn swing or similar article, substantially as shown and described.

ALBERT H. ADCOX.
